MAGNETO OR DYNAMO ELECTRIC MACHINE.

SPECIFICATION forming part of Letters Patent No. 333,902, dated January 5, 1886.

Application filed December 10, 1883. Serial No. 114,038. (No model.) Patented in France October 11, 1883, No. 158,007; in Italy October 23, 1883, No. 16,034; in Germany November 6, 1883, No. 29,836; in Belgium November 23, 1883, No. 63,315; in England December 8, 1883, No. 5,682; in Russia January 11, 1884, No. 7,005; in Canada January 17, 1884, No. 18,563; in Austria-Hungary March 4, 1884, No. 44,198 and No. 10,003, and in Spain June 13, 1884, No. 3,892.

To all whom it may concern:

Be it known that I, RENÉ THURY, a citizen of the Republic of Switzerland, residing in Geneva, Switzerland, have invented certain new and useful Improvements in Dynamo-Electric Machines, (for which I have obtained Letters Patent in Great Britain, No. 5,682, December 8, 1883; Spain, No. 3,892, June 13, 1884; Canada, No. 18,563, January 17, 1884; Italy No. 16,034, October 23, 1883; Austria-Hungary, No. 44,198 and No. 10,003, March 4, 1884; Belgium No. 63,315, November 23, 1883; France, No. 158,007, October 11, 1883; Germany, No. 29,836, November 6, 1883, and Russia, No. 7,005, January 11, 1884,) of which the following is a specification.

The object of my invention is to remedy the numerous defects which are met in the use of dynamo-electric machines generating a continuous current, and intended for the production of electric light, transmission of motive power, or applied to electro-metallurgy. The defect common to all machines of this class is the great speed of rotation required, which causes wear upon the parts exposed to friction, frequent accidents, and the loss of considerable power. A second defect is the little energy which is obtained from a machine which might produce much more if it were possible to increase its peripheral speed. The increase of that speed would give a greater production and more useful effect. A third very grave defect in machines of large size is the production of sparks at the contact-points of the brushes with the commutator. Moreover, all of these machines are generally delicate. If a brush happens to be displaced or to be worn out, the current may be completely interrupted.

The difficulties which are experienced in the construction of practical machines are the following: The construction of induction-armatures of large size with a slow speed necessitates powerful inductors, the usual dispositions of which have all the great inconveniences of employing only a part of the effect-

ive magnetic field. The sparks on the collector proceed from the interruption of a portion of the principal circuit at the moment when the brushes leave each commutator-section. They can only be avoided by using a great number of broad brushes. Hence it is very desirable to arrive at a division of the armature into a certain number of parts each of which will develop a certain part of the current. In that manner a machine, however powerful, would always be composed of a certain number of smaller machines. The machine is thereby rendered less delicate, the contact of a brush may cease without interruption of the current, and the machine continue to act until the contacts are re-established. The sparks which are produced at the brushes depend also on the relative resistance of each section of the armature. The greater the resistance the stronger are the sparks for the same current. This resistance is, likewise, the cause why the machine becomes hot, and the electro-motive force experiences variations when a current more or less intense is used with a constant speed of the generator.

My invention consists of a new system of distribution of the electric conductors (wires) upon the armature of a dynamo-electric machine, and relates especially to the reduction of the resistance in the armature by diminishing as much as possible the amount of wire forming a part of the helices arranged thereon which is out of the magnetic field, and which is not or but little influenced, and also to the method and means employed to collect the current induced in the armature-helices.

My invention also relates to a new method of arranging the magnets, permanent or induced, which, with their field-pieces, form the magnetic field within which the armature revolves.

In the accompanying drawings, which represent my invention, similar letters of reference indicate like parts, in which—

Figure 1 is a front elevation of a dynamo-

electric machine constructed according to my invention. Fig. 2 is an end view of the same, showing the arrangement of the field-magnets, and also the method by which the contact-brushes are joined together. Fig. 3 is a transverse section taken through the line x - x of Fig. 1. Fig. 4 is a vertical section. Fig. 5 is a diagrammatic view showing the method of winding upon the armature-drum the rectangular helices which make up the induction-armature. Fig. 6 is a diagram which illustrates the position on the ends of the armature-drum of the wires (chords) which form the end wires of the rectangular helices arranged on the armature, and also the system by which the several helices are connected.

My inductor is composed of a polygonal permanent or electro magnet. The like poles of the neighboring separate magnets are joined together and fixed to pole-pieces alternately north and south, lodged within the spaces extending between the internal angles of the polygon and the included drum. In that manner my inductor assumes externally the shape of a great polygon, while the inside has a cylindrical shape fitting very nearly that of the armature. I fix this polygonal inductor, as well as the bearing for the armature, upon a frame of cast-iron, taking care to insulate magnetically the former from it.

In the drawings, A A are the permanent or electro magnets, to which it is preferable to give a rectangular shape, but which may also be round, or have any form whatever.

P P are the pole-pieces, made in such a manner as to envelop or surround nearly three-quarters of the surface of the drum, and disposed so as to fill the interior angles of the magnetic polygon.

The number of magnets used to form my polygonal inductor I prefer to have equal to the denominator of that fraction of the circumference of the armature adopted for the winding or size of the rectangular helices arranged thereon. In other words, if in the scheme adopted for the division of the armature the chord formed by an end wire of one rectangular helix, in passing over the end of the armature-drum, is in length equal to one-sixth of the circumference of the drum, then the number of magnets used would be six. If one-eighth, eight magnets would be required.

In principle my armature consists of a drum, magnetic or not, fixed on an axis of rotation, and upon which are disposed a number of rectangular helices formed from consecutive windings of a single continuous wire and connected electrically to each other. In winding the helices the wires which form the sides of the rectangles are placed longitudinally upon the surface of the armature-drum, parallel to each other and to the axis, and the wires which form the ends of the rectangular helices are carried across opposite ends of the drum, through chords of the circumference of the drum, each of which divides the latter in four, six, or any even number of parts, in-

stead of turning backward and passing inside, as in the Gramme ring, or turning round the axis to rejoin the conductor diametrically opposite, as in the Heffner-Alteneck coil.

T is the movable drum upon which the wire forming my armature is arranged. This drum is fixed upon an axis, and is composed of metal disks K, Fig. 4, bearing upon their circumference an insulating-cylinder, I, upon which is wound a magnetic mass, M, preferably of iron wire. Upon this mass, intended for the strengthening of the lines of force of the magnetic field, are wound the armature-helices in the manner shown in Figs. 5 and 6.

As before stated, the sides of the rectangular helices are wound parallel to the axis of rotation, and on the surface of the drum.

In Fig. 5 are shown the wires 1 2 3 4, placed parallel to each other.

In the machine shown in the drawings the armature is supposed to be divided into six parts, and each of the wires which form the ends of the rectangular helices passes over the ends of the drum through a chord equal to the radius—namely, the sixth part of the circumference. In Fig. 6 the double heavy line a a represents such a chord in length equal to one-sixth of the circumference. Three pairs of such heavy lines are shown arranged equally distant from each other. By measurement it will be found that the sum of the length of these lines will be equal to one-half the circumference of the drum, and the sum of the spaces included between the ends of said lines will also be equal to one-half the circumference. Thus the circumference divided by the length of any one of the lines or of an intervening space will give a number showing that each line or space represents one-sixth of the circumference.

I have indicated the separate helices in the diagram in a different manner, so as to show plainly that the wire forming each helix gives the same length of chord in passing over the end of the drum. The wire forming the helices is a single endless one. The wire 1, for instance, is connected with the wire 6 in such a manner that the end of 1 forms the beginning of 6. The wire 3 is connected in the same way with 8, and so on up to the last, which in its turn is connected with the beginning of the first.

In Figs. 3 and 4 the wires are shown to form nine rectangular helices, which are so disposed on the armature-drum that the ends of each helix overlap, or are overlapped by the ends of two other helices arranged one on each side. Thus each helix makes a kind of frame surrounding a fraction of the drum, which in this scheme is a sixth, although the number of helices is nine. Thus it will be seen that while the lengths of the chords formed by the end wires of the nine helices, in passing over the ends of the drum, are each equal to the radius, the sum of their lengths is one-half time greater than the circumference.

Let us follow the wire 4, setting out in the

direction of the arrows, Fig. 5. It follows the exterior surface of the drum and reaches one of its extremities, which it crosses and forms the chord a , equal to the radius in the present instance, and returns to the other end 5 of the drum by the wire 1, parallel to the wire 4 and to the axis, and thence, as the connecting-wire a' , it goes to the wire 6, and through the chord b to wire 3, through connecting-wire b' to the wire 8, and so on over the whole 10 exterior surface of the drum. The circuits thus formed, $4 a 1 a'$ or $6 b 3 b'$, may also be doubled or multiplied at will, as shown in Fig. 15 5, forming the rectangles $4 a 1 a' 4 a 1 a'$, or $6 b 3 d' 6 b 3 b'$.

In Fig. 6 the method of electrically connecting the helices together is illustrated by the dotted lines. All the helices, as before stated, are formed from consecutive windings 20 of a single continuous wire, the ends being joined to form a closed circuit, and hence when the machine is in operation a current will be circulating in all of the wires of the armature, and there will be no idle helix, 25 although certain helices, when in a neutral position of the field-magnets, will not be contributing to the electro-motive force of the system. There will, however, be no break in the circuit, either as regards the circuit as a 30 whole or as regards any individual portion of the armature-circuit. The induced currents in the armature can be commutated in series or in multiple, as preferred. In the present case, where an even number of poles is used 35 in the inductor, an odd number of sections to the commutator is required. In the drawings, Figs. 3 and 5, it will be seen that three sides of three separate rectangular helices are under each pole.

To determine the number of commutator-sections required, it is only necessary to multiply the number of sides of the separate rectangles arranged under each pole by the number of poles composing the inductor. In the 40 present case the number of poles used is six, and hence there would be eighteen sides, which divided by the numeral 2, as there are two acting sides of each rectangle, gives nine—the number of commutator-sections required. 45 With four or eight poles in the inductor an even number of sections would be required. Thus an even or odd number of commutator-sections may be used with an even number of poles. The helices are connected together 50 in such a manner as to form what may be called "nine double helices," each one of which is composed of two simple helices, and each simple helix forms a right-hand helix in one double helix, at the same time forming a 55 left-hand helix of another double helix arranged contiguous thereto, and such double helices are each connected to one section of the commutator C by a suitable wire, l , proceeding from the connecting-wires $a' b' c'$. By 60 this method of connection a double helix is never out of use, as at such times when the wires forming one side of a simple helix oc-

cupy a neutral position between the poles of the field-magnets the other side of the same simple helix also occupies a neutral position, 70 and so will not be contributing to the electro-motive force of the system. Thus, as regards external coil or line, a simple helix will, by reason of a brush lapping or bridging succeeding commutator-sections arranged opposite thereto, and to which the ends of the simple helix are connected, be short-circuited, or a very little current circulating therein as it passes neutral points in the magnetic field; but the other simple helix in such a double 75 helix will be in that position where it develops the maximum electro-motive force, so that the total electro-motive force of a double helix will not materially vary, and will be constant and uniform. D' D' are the collecting brushes, each 80 of which is divided into two or more parts, for convenience of adjustment, and arranged to rest upon the commutator-sections at one end of the machine. The brushes are supported by the adjustable brush-bearers D D, arranged 85 upon a wheel or star, F, and so arranged as to be movably adjustable around a tubular bearing fixed upon the pedestal. The number of brushes employed corresponds with the 90 number of magnets used in the inductor, and also to the scheme of division of the armature. Thus if a scheme of division of the armature in six or eight parts be adopted the six or 95 eight brushes corresponding to these divisions united three or four together enable me to 100 produce a machine of great power composed of several weak machines. Every pair of brushes has to transmit but a third or fourth part of the whole current, and the production of sparks is reduced in the same proportion. 105

In the drawings, Figs. 1 and 2, six brushes are shown arranged equidistant from each other, alternately positive and negative in their circular order. Those of the positive series are electrically connected together by 110 means of an arc-shaped plate, F', arranged on the outer side of the arms of the star F, and those of the negative series by a similar plate, F'', upon the inner side of the arms of the star. Each of these plates is connected to all of the 115 arms of the star over or under which it passes; but each plate is insulated from those arms which support brushes other than those which it is designed to electrically connect.

The method of arranging the brushes in the 120 star F enables me to vary the angle of all the brushes when they are wedged up, and so change the direction of the current by turning the whole system of brushes, (in the present case one-sixth of a revolution.) This is 125 advantageous for the preservation of the brushes, as the positive always wear out sooner than the negative.

B B represent the cast-iron frame carrying 130 the pedestal and bearings, as well as the polygonal field-of-force magnets, the latter fixed and supported by means of frame E, made of any non-magnetic material.

Each of the armature-helices may be com-

posed of any number of convolutions of wire. In the drawings only two are represented. The wires uniting the helices with the sections of the commutator series can be arranged as 5 indicated by the dotted lines at l' in Fig. 3.

I claim as my invention—

1. A dynamo - electric machine provided with an armature consisting of a drum upon which are disposed helices formed from a continuous wire and wound in consecutive order around the surface of the drum, the end of one helix forming the beginning of the next, and having their sides parallel to each other and to the axes of rotation, and whose ends 15 pass over the ends of the drum as chords, dividing it into any equal number of parts.
2. A dynamo - electric machine provided with an induction-armature consisting of a drum upon which is wound, at right angles 20 to the axis, a mass of iron wire or other magnetic material, upon which is disposed a number of rectangular helices formed from consecutive windings of a continuous wire whose sides are parallel, and whose ends pass over 25 the ends of the drum as chords of the circumference of the drum, dividing the latter into any even number of parts.
3. In a dynamo-electric machine, an armature consisting of a drum upon the surface of 30 which are arranged rectangular helices formed from consecutive windings of a continuous wire whose sides are parallel, and whose ends pass over the ends of the drum as chords of the circumference, each helix united to two 35 succeeding commutator - segments through long chords crossing one end of the drum, substantially as described.
4. In a dynamo-electric machine, an armature upon which are disposed rectangular helices formed from consecutive windings of a 40 continuous wire, the said helices divided into sets of two and united through a long chord on the end of the armature to form a double helix, and in which each single helix forms one-half 45 of a double helix next preceding or succeeding it, and to which it is similarly connected, and each of said double helices connected to one segment of the commutator, substantially as described.
5. The combination of the polygonally - arranged magnets, the field- pieces formed and located as described, and an armature consisting of a drum upon which are disposed, parallel to the axis, rectangular helices wound in 50

consecutive order around the surface of the 55 drum, the ends of which pass over the ends of the drum as chords, corresponding in length with the fraction of the circumference, as determined by the number of magnets forming the magnetic polygon.

60

6. In a dynamo - electric machine, and in combination with the system of field-magnets and their pole-pieces, an armature upon which are arranged rectangular helices united on the end of a drum through a long chord, to form 65 double helices, and commutator-segments corresponding in number with the helices, substantially as described.

70

7. In a dynamo-electric machine, the combination of the system of field-magnets and 75 their pole-pieces, an armature upon which are arranged rectangular helices united to form double helices, commutator - segments corresponding in number with the helices on the armature, and collecting-brushes corresponding in number with the magnets in the inductor, substantially as described.

75

8. In a dynamo electric machine, the combination, with the inducing - magnets, of the armature composed of the drum T, disks K, 80 insulating-cylinder I, magnetic mass M, and the rectangular coils of wire formed thereon, substantially as described.

85

9. The combination, in a dynamo-electric machine, of an inductor having an even number of field-poles, with an armature upon which 85 are disposed an uneven number of helices formed from consecutive windings of a single continuous wire, helices united together in pairs to form an uneven number of double 90 helices, substantially as described.

10. The combination, in a dynamo electric machine, of an inductor having an even number of field-poles, with an armature upon which 95 are disposed, parallel to the axis of rotation, an uneven number of helices formed from consecutive windings of a continuous wire whose ends pass over the ends of the drum as chords, corresponding in length with the fraction of the circumference as determined by the number of magnets forming the inductor.

100

Signed by me this 22d day of October, A. D. 1883.
